DESCRIPTION

FIG. 1 is a front view of a pull tab for a slide fastener slider of the claimed design, the rear view being identical.

FIG. 2 is a plan view of the pull tab of FIG. 1.

FIG. 3 is a base view of the pull tab of FIG. 1.

FIG. 4 is a right side view of the pull tab of FIG. 1, the left side view being identical.

FIG. 5 is a perspective view of the pull tab of FIG. 1; and, FIG. 6 is a front view of the pull tab shown in a position of use with a slide fastener.

It being understood that the broken line showing of a slide fastener is for illustrative purposes only and forms no part of the claimed design.
